INTERNAL-COMBUSTION ENGINE.

1,352,945.

Specification of Letters Patent. Patented Sept. 14, 1920.

Application filed October 4, 1915. Serial No. 53,927.

To all whom it may concern:

Be it known that I, THOMAS J. FAY, a citizen of the United States, residing at Brooklyn, in the county of Kings and State 5 of New York, have invented a certain new and useful Improvement in Internal-Combustion Engines, of which the following is a full, clear, and exact description, reference being had to the accompanying drawings.

10 This invention relates to internal combustion engines and has particular reference to that type of engine wherein a sliding exhaust valve is employed, although 15 many features of my invention are applicable to engines of whatever type. The objects of my invention are the provision of an internal combustion engine which shall be peculiarly free from carbon deposition 20 and heat loss; the provision of a type of cylinder which shall permit the interior of all gas contacting chambers to be smoothly machined or otherwise surfaced; the provision of new and improved arrangements 25 for igniting the charge whereby a more perfect combustion and a more uniform cylinder pressure are secured; the provision of a new and improved arrangement for cooling the cylinder head; the provision of 30 means for cooling the pistons; the provision of new and improved construction of valve chambers and valves; while further objects and advantages will become apparent as the description proceeds.

35 Heretofore it has been the custom to machine only the portions of the cylinder castings which come directly in contact with moving parts or engaging surfaces, the interior of valve chambers, connecting ports, 40 etc., being left rough and unfinished. Accordingly the volume of these has frequently varied slightly in the different cylinders of the same engine, thus causing a slightly unequal operation, while the rough and un- 45 finished character of the surfaces has facilitated the deposition of carbon thereon, impeded the removal of the carbon, and tended to extract heat from the gases at an unduly rapid rate. I have found that if the 50 interior of all parts of the various cylinders be made to exactly the same size, the regularity of engine operation will be noticeably improved; also that if the entire cylinder interior is machined to a perfectly 55 smooth surface, the deposition of carbon

will be much diminished while its adhesion will be much less tenacious, these phenomena being particularly acute in case the cylinder interior after machining be plated or coated with some substance which is particularly smooth and is particularly averse to absorbing or transmitting heat. For such a coating nickel, either alone or alloyed with silver is peculiarly satisfactory, owing to resistance to heat deterioration, its brightness and smoothness, and its resistance to tarnish. However I do not confine myself to these materials, nor even to a metal covering, since my invention also comprehends the employment of non-metallic films or 60 coatings. Whatever the covering employed it will ordinarily be necessary to machine all gas contacting surfaces wherefore I have provided a new and improved cylinder design whereby the machine work may be facilitated and whereby the other objects hereinbefore recited may be accomplished, and this design, forms one of the aspects of 65 my present invention, although it will be apparent that certain features of my invention can be equally well achieved with 70 the employment of other designs.

In the drawings accompanying and forming a part of this application I have illustrated the type of engine which I now prefer in conjunction with the improvements contained in my present invention, and in these drawings: Figure 1 is a top plan view of an engine constructed in accordance with my invention, a portion of the same being 75 broken away upon the section line 1—1 of Fig. 3; Fig. 2 represents a side elevational view of my improved engine, certain parts being broken away and shown in section for purposes of clearness; and Fig. 3 is a 80 vertical sectional view taken upon the line 3—3 of Figs. 1 and 2 and looking in the direction of the arrows.

Describing by reference characters the parts shown in the drawings, 1 represents the crank case of an internal combustion engine having its upper end faced as at 2 for the reception of the cylinders 3 which are preferably cast *en bloc*, a four-cylinder engine being illustrated in the present case. 105 Adjacent to their upper ends, these cylinders are formed at one side with the horizontally projecting hollow branches 4—4, and at the other side with the similar but shorter hollow branches 5—5, the axes of all said 110

branches being transverse to the axis of the crank case. Each of the branches 4-4 merges with a pair of hollow barrels 6 and 7, respectively, the same being arranged one 5 on each side of the branch 4 and with their bores vertical and partially intersecting the bore of that branch. The upper ends of the barrels are connected by a flat plate 8 which forms a seat for the inlet and exhaust 10 manifolds, while the lower ends of said barrels are connected by a plate 9 which forms the upper wall of the casing for the valve shaft. The outer ends of the branches 4 are connected by a vertical plate 10 and the 15 outer ends of the branches 5 by the vertical plate 11, said plates being connected by a wall 12 outside of the terminal cylinders whereby a water jacket is provided. The plate 8 is extended laterally as shown at 13 20 so as to connect the upper ends of the cylinders 3-3, to receive the water manifold and cylinder heads. All of these parts comprise a single casting, and the machining of the same consists of facing the top and bottom, boring and reaming the main cylinders 3 together with the barrels 6 and 7, and finally boring and surfacing the interior of the branches 4 and 5 by means of a boring tool or reamer operated upon a transverse 25 axis. The outer ends of the branches are threaded for the reception of the spark plugs 14 and 15, respectively, while the inner ends of the branches 5 are reamed out to provide flaring recesses or bays 16. This 30 may be done by means of a tool located inside the cylinder and operated by a shank extending through the opposite branch 4. Its purpose is to provide a recess for the terminals of the spark plug 15 so that the 35 same may be located at one side of the piston but without the provision of any oil-holding pockets. As a consequence of these manipulations the entire interior of the cylinder casting is machined in a rapid and efficient 40 manner.

Each of the cylinders is provided with a piston of the barrel type, comprising an elongated cylindrical wall 20 closed at its upper end by a head or web 21. The upper 45 end of each cylinder is closed by means of a circular plate 22 provided with an annular flange 23 adapted to fit into a groove 24 formed in the plate 13 concentric with that cylinder. The lower side of said plate is 50 provided with a hollow extension 25 projecting down into said cylinder to a position at least as far as and preferably slightly beyond the walls of the bosses 4, 5. Suitable packing, preferably of a substantially in- 55 compressible nature, is introduced into the groove 24, while above the plate 22 is laid a softer packing 26 above which is securely bolted the upper manifold 27 which communicates with the various extensions 25 by 60 means of the passageways 28. This mani-

fold is preferably made of sufficiently flexible metal to permit the variation of adjustment required to hold all the cylinder heads in gas-tight relation. Cooling liquid may be supplied to or from this manifold in any 70 suitable manner as by the connection 29, while communication may be established between said manifold and the cylinder water jacket in any suitable mode as by means of the connecting plate 30 surrounding the passageway 31 as shown in Fig. 2. The expression "water-jacket" is taken as denoting any closed space of whatever shape adapted for receiving cooling fluid of whatever nature. 75

In previous devices difficulty has sometimes been experienced through an overheating of the piston head, the walls of the piston being sufficiently cooled by contact with the cylinder walls, but the end web being heated frequently to redness, which 80 causes warping or binding of the piston, gas leakage, cracking of the piston, and sometimes premature firing of the charge. By suitable arrangement of the main crank 85 32 and connecting rods 33 I bring the head 90 web 21 at its maximum elevation very near the end of the extension or water jacket 25 so as to permit the efficient transfer of heat, and in this way reduce markedly the temperature of the piston head. This arrangement also transfers the greater part of the 95 compression space out of the cylinder itself and into the branches 4 and 5. This compression space being of elongated narrow shape, the combustion of the gases therein 100 will be slower than in the case of a more compact gas space. Ignition is effected simultaneously at opposite ends by the spark plugs 14 and 15 one of which is comparatively near the cylinder. The downward 105 movement of the piston 20 relieves the pressure to some extent at a point near the spark plug 15 wherefore the combustion pressure generated adjacent the spark plug 14 forces the entire contents of the branch, both 110 burned and unburned, into the cylinder 3. The proportions of burned and unburned gases will ordinarily vary with the engine speed, the mixture condition, and the time of igniting: thus with a low speed, a good 115 mixture, and an early spark it is possible that the entire charge will have been ignited prior to any material movement of the piston; while at higher engine speed, poorer mixtures, or later ignition, it is possible that 120 some of the contents of the branch 4 would be ejected into the cylinder 3 before the arrival of the flame. In order to insure the completest possible combustion of the charge I preferably locate each of the branches 4 125 off-center with respect to its cylinder as shown in Fig. 1, so that the ejection of its contents into the cylinder shall set up a swirling action which will thoroughly mix the gaseous contents thereof and will result 130

in complete combustion. The expedient of constructing the compression chamber so as to arrange the gas in an elongated column rather than in a compact body renders its 5 combustion slower and more uniform and hence produces a more uniform cylinder pressure. Also the arrangement here described produces an injection of combustible mixture into an ignited mass within the 10 cylinder, thus maintaining high efficiency coupled with noiselessness. It will be seen that the expansion caused by the combustion of the gases adjacent the spark plug 14 acts like a piston to eject the unburned 15 gases into the cylinder where combustion has already been initiated by the spark plug 15, therefore my invention contemplates a device wherein the unburned gases are injected into the cylinder during the combustion in 20 the cylinder. The elongated shape of the combustion chamber and the consequent large surface renders peculiarly desirable the use of some expedient to minimize heat loss, such as the smoothing, plating, or coating 25 above described.

Within the requirements of the invention so far described, any usual or suitable valve construction could be employed, although I have illustrated here and at present prefer 30 to employ valves of the slideable or piston type. In the embodiment here illustrated a pair of cylindrical sleeves 35—36 are introduced, one into each end, of each of the barrels 6, 7, their adjacent ends being spaced 35 apart to provide an annular slot or passageway 37 as shown in Fig. 2, and the adjacent ends of the sleeves being exteriorly reduced in size as shown at 38 so as to provide an annular passageway surrounding the sleeves 40 and communicating with the interior of the boss 4, thus conveying the gases to all parts of the slot 37 and maintaining all sides of the sleeves at substantially uniform temperatures and pressures whereby binding, 45 leakage, and sticking are minimized. Slidably mounted inside each pair of sleeves is a piston 40 connected by means of the pitmen 41—41 with the multiple crank shaft 42, the cranks being so arranged as to reciprocate these pistons in proper phase for 50 inlet and outlet purposes.

In the embodiment here shown the barrels 6—6 are employed as inlet valves and the barrels 7—7 as outlet valves. To the 55 upper face of the plate 8 is secured a hollow elongated cast metal box 45 divided into two longitudinal chambers by means of the partition 46, the lower edge of said partition being deflected first to one side and then to the other as illustrated in Fig. 1 so as to place all of the inlet valves in communication with the inlet manifold 47, and all the outlet valves into communication with the outlet manifold 48. The shaft 42 is 60 illustrated as journaled inside a closed cas-

ing provided by the skirt 50 and cap 51, and is driven from the main shaft 52 by means of a sprocket 53 and chain 54, or other convenient transmission, an inclosing box 55 being preferably employed. However the 70 method of constructing and operating these valves is not claimed in the present specification but is fully recited in the claims of my copending application filed October 4, 1915 Serial No. 53,926. Also it will be obvious that many of the features of my present invention could be employed in connection with a totally different kind of valve and valve operating means. While I have described my invention in detail I do not 75 therefore propose to be limited to such details except as the same may be positively included in the claims hereto annexed or may be rendered necessary by the prior state of the art.

Having thus described my invention, what I claim is:—

1. In an internal combustion engine, a compression chamber of elongated narrow shape communicating with the engine cylinder at a point adjacent one end of said chamber, and means for simultaneously igniting the mixture at both ends of said chamber.

2. In an internal combustion engine, a cylinder, a compression chamber communicating therewith, means operative upon the termination of the compression stroke for igniting the mixture in the cylinder, and means for thereafter injecting into said cylinder the contents of said compression chamber.

3. In an internal combustion engine, a cylinder, a compression chamber located outside of the same and communicating therewith by means of a port whose axis is transverse to and eccentric to the cylinder axis and means operating upon the end of the compression stroke for igniting the mixture in said chamber at a distance from said cylinder.

4. In an internal combustion engine, a cylinder, a narrow elongated compression chamber arranged transversely thereto and communicating therewith out of line with the cylinder axis, and means operating upon the conclusion of the compression stroke for simultaneously igniting the mixture at both ends of said chamber.

5. In an internal combustion engine, a cylinder formed adjacent to its head end with a pair of oppositely projecting, hollow, cylindrical, transverse branches, one of which is longer than the other, and spark plugs secured in the ends of both branches.

6. In an internal combustion engine, a cylinder formed adjacent to its head end with a pair of oppositely projecting, hollow, cylindrical, transverse branches, one of which is longer than the other inlet and

outlet valves communicating with the longer of said branches and spark plugs secured in the ends of both branches.

7. In an internal combustion engine, a cylinder formed adjacent to its head end with a pair of oppositely projecting, hollow, cylindrical, transverse branches, one of which is longer than the other, inlet and outlet valves communicating with the longer branch, and spark plugs secured in the ends of both branches, the mouth of the shorter branch being reamed out to provide a flaring bay.

8. In an internal combustion engine, a plurality of cylinders, an independent hollow head for each cylinder, each head having a hollow extension fitting into its cylinder and having its upper side faced, and a hollow manifold secured over all of said heads and holding them in place, all of said heads

having openings communicating with said manifold.

9. In an internal combustion engine, a plurality of cylinders, an independent hollow head for each cylinder, each head having a hollow extension fitting into its cylinder and having its upper side faced, and a hollow manifold secured over all of said heads and holding them in place, all of said heads having openings communicating with said manifold, said manifold being of slightly flexible material so as to compensate for variations in the level of said heads. 25

In testimony whereof, I hereunto affix my signature in the presence of two witnesses. 30 35
